UNITED STATES PATENT OFFICE.

GEORGE E. HERLIHY, OF NEW YORK, N. Y.

ADVERTISING DEVICE.

Application filed August 10, 1921. Serial No. 491,080.

To all whom it may concern:

Be it known that I, GEORGE E. HERLIHY, a citizen of the United States, residing at New York city, borough of Manhattan, in the county and State of New York, have invented a certain new and useful Advertising Device, of which the following is a specification.

This invention is an advertising device and more particularly an advertising sign adapted to be positioned in the corridors or foyers of theaters or on the sidewalks in front of theaters, and is so constituted that it will not only serve to exhibit the theatrical bill, but in addition thereto will serve as an advertising medium for various articles of manufacture entirely independent of the theatrical program.

From a more specific standpoint, the invention embodies an advertising sign in the form of a frame in which is adapted to be positioned a theatrical bill or program which occupies a conspicuous place in the arrangement and is intended for the advertisement of the particular show playing in the theater. The device is further constituted to hold several additional and smaller advertisements which are conspicuously positioned, so that a person reading the program or bill of the theater will be sure to see the advertising matter directly adjacent thereto.

Of especial importance in the sign of the present invention is the fact that the device is so constructed as to enable the proprietor of the theater to daily change the theatrical program or bill without having access to the advertising cards carried in the sign. If the theatrical manager were able, he would be apt to remove the advertising matter from the frame of the sign and insert in lieu thereof pictures of the players and other theatrical advertising matter.

In the present invention, a certain part of the sign only is allotted to the theatrical manager for his advertising and the frame of the sign is so constructed that he cannot gain access to the other advertising signs.

In its preferred form, the invention embodies a frame having a plurality of panels, the center panel of which is preferably made larger than the rest and is adapted to contain the theatrical bill poster. Access may be had to this panel by a separate door or closure associated therewith and adapted to be normally locked in closed position by a key held by the theatrical proprietor. The other

panels are each adapted to contain advertising show cards, but each of these other panels are independent of the main panel and are independently locked in closed condition by a different key held by the company which owns the sign. All of the panels have glass fronts, so that the contents of each panel may be readily seen from the front of the sign.

Features of the invention, other than those specified, will be apparent from the herein-after detailed description and claims, when read in conjunction with the accompanying drawings.

The accompanying drawings illustrate one practical embodiment of the present invention, but the construction therein shown is to be understood as illustrative, only, and not as defining the limits of the invention.

Figure 1 is a perspective view of an advertising sign embodying the present invention.

Figure 2 is a section on the line 2—2 of Figure 1.

Figure 3 is a section on the line 3—3 of Figure 1; and,

Figure 4 is a back view of the sign.

The sign shown in the drawings embodies a frame 1 provided with feet 2 and adapted to be supported in upstanding position by means of pivoted rear legs 3. This frame may be of any desired shape and may be ornamented in any suitable way, but, for the purpose of illustration, it is shown plain and of substantially rectangular form.

The face of the frame is divided off by strips 4 into a plurality of panels and while this division may vary, I preferably provide the frame with a large center panel 5, surrounded by a plurality of smaller marginal panels 6. Each panel is in the form of a chamber, the front of which is closed by glass, the center panel 5 being closed by a plate of glass 7, and each of the other panels by smaller plates of glass 8. Back of each plate of glass is a chamber adapted to contain a show card. The chambers of the smaller panels 6 are positioned directly back of the frame 1 and are closed by a back plate 9, while the chamber of the panel 5 is set back further than the smaller surrounding panels and is closed by a back plate 10.

In order that a theatrical bill poster may be positioned within the chamber 5a of the center panel and between the glass 7 and 110

back 10, one side of said chamber is provided with a closure in the form of a strip 11. The other three sides of the chamber are closed permanently, but the strip 11 is removable to permit access to the interior of the chamber 5^a. The strips 4 which surround the center panel are interiorly grooved as at 13 and this is also true of the strip 11, so that when the strip 11 is removed, the pane of glass 7 may be slipped into the grooves as shown best in Figures 2 and 3, and thereafter a theatrical bill poster introduced back of the pane of glass, whereupon the strip 11, which constitutes the removable side of the chamber 5^a may be replaced as shown in Figure 3 and locked in position by a padlock passed through staples 12.

Figure 4 very clearly shows the manner in which the removable side of the chamber 5^a may be removed for the purpose of inserting the glass 7, as well as for changing the bill posters. The key of the padlock for locking this false side in position is adapted to be handed over to the theatrical proprietor, so that he may change the posters when he desires. The lower central panel designated 6' is provided at its back with a door 14, hinged at 15 and adapted to be locked by a hasp 16, a keeper 17 and by an associated padlock 18, while all of the other panels 6 are adapted to be closed and locked in the same manner as the panel 5. In a similar way access may be had to the upper center panel by virtue of its removable side 19, while access may be had to either lateral tier of panels by removing their removable sides 20. The panels of each of the lateral tiers may be independently closed if desired, but I find it more convenient to close them collectively by long strips 20, as shown, which form the removable sides of all five panels of each tier. The removable side 19 may be locked in place by a padlock 21 while the removable sides 20 may be similarly secured in position by padlocks 22.

In practice, the padlocks 18, 21 and 22 are preferably all responsive to one key, so that the advertising man may readily gain access to all the panels, though not necessarily the panel 5, while the proprietor of the theater can gain access to only the panel 5.

In the accompanying drawings, the sign is shown as it would be constructed of wood, though, in practice, the same may be constructed of metal, without departing from this invention and while the sign is illustrated as having thirteen panels, these panels may vary in number and in placement, as well as in shape. In practice, the sign is preferably made highly ornate and it is provided with electrical connections

supporting a lamp or cluster of lamps at its top, so as to illuminate the face of the sign after the manner common in advertising signs. This illuminating feature, however, forms no part of the present invention, which is directed essentially to a sign having one or more compartments for theatrical advertising, which compartments are accessible to the proprietor of the theater, and other compartments for other advertising matter which are not accessible to the proprietor of the theater.

The construction shown in the drawing is particularly adapted to carry out this intention, especially in view of the center compartment or panel which is set back of the other panels, so that the advertising matter in the center panel is in a different plane than the advertising matter in all the other panels. This arrangement produces a very pleasing and aesthetic effect and imparts to the sign highly decorative properties, so that it will not be unsightly and detract from the appearance of the theater foyer or entrance.

It will be understood that the specific invention described may be modified in formal respects, such as by the substitution of equivalents, and that parts of the complete construction described may be used alone, or in other environments, without departing from the spirit or substance of the broad invention, the scope of which is commensurate with the appended claims.

Having thus fully described the invention, what I claim as new and desire to secure by Letters Patent is:

1. An advertising sign embodying a plurality of closed compartments or chambers, each of which is adapted to house an advertising and show card, the majority of which compartments lie in the same plane and at least one of which lies in a different plane, and means for permitting access to the interior of the compartment in one plane to the exclusion of the compartment in the other plane and vice versa.

2. An advertising sign embodying a frame provided with a plurality of closed compartments or chambers lying in substantially the same plane, and at least one additional compartment or chamber lying in a different plane, said compartments serving to use advertising and show cards, separate closures for the compartments of both planes, and means for independently locking the compartments of both planes in closed condition, so that the compartment of one plane will be inaccessible to a person opening the compartment of the other plane or vice versa.

3. An advertising sign embodying a plurality of closed compartments, the majority of which lie in the same plane and at least

one of which lies in a different plane, said compartments serving to house advertising and show cards, means for permitting access to the interior of the compartments in one plane to the exclusion of the compartment in the other plane and vice versa, footing means and means for supporting the sign in upstanding position on the footing means.

4. An advertising sign embodying a frame, the face of which is divided up into a plurality of panels back of each of which is a compartment, a glass front for each compartment, certain of the compartments being in one plane and at least one of the compartments being in a different plane, closures for said compartments, the closures of the compartment in one plane being independent of the closures of the compartments in the other plane, and means for separately locking said closures in position so that the closures of one plane may be locked while the closure of the other plane is opened and vice versa.

5. An advertising sign embodying a central closed compartment, a plurality of additional closed compartments positioned around all four sides of the central compartment and positioned forwardly thereof, removable sides on the several compartments to permit a pane of glass to be positioned in each compartment and an advertising card to be positioned in each compartment back of the glass, and means for locking the movable sides of the compartments in position.

6. An advertising sign embodying a frame, a plurality of strips extending across the back of the frame for dividing the confines of said frame into a plurality of sections, means mounted on the back of certain of said strips to form compartments back of certain of said sections, a transparent front associated with each of such compartments, closures also associated with such compartments so as to preclude the removal of advertising show cards positioned within the compartments by unauthorized persons and to house such show cards in normally closed compartments, means positioned at the back of certain of the strips to form an additional compartment, a closure for such additional compartment, and a transparent front in such additional compartment, whereby a show card may be housed in such additional closed compartment, and means for locking the closure of said additional closed compartment to prevent the removal of the last mentioned show card by unauthorized persons.

7. An advertising sign embodying a frame, a plurality of strips for dividing the confines of the frame into a plurality of sections, means associated with each section for forming each section into closed compartments having transparent fronts, closures, for said compartments, and locking means for said closures, all of said closures being positioned rearwardly of the frame and concealed by the frame from view from in front of the frame.

8. An advertising sign embodying a frame, a plurality of strips for dividing the confines of the frame into a plurality of sections, means associated with each section for forming each section into closed compartments having transparent fronts, closures for said compartments, and locking means for said closures, all of said closures being positioned rearwardly of the frame and concealed by the frame from view from in front of the frame.

9. An advertising sign embodying a frame, a plurality of strips for dividing the confines of the frame into a plurality of sections, means associated with each section for forming each section into closed compartments having transparent fronts, closures for said compartments, and locking means for said closures, all of said closures being positioned rearwardly of the frame and concealed by the frame from view from in front of the frame, the majority of the compartments being in the same plane and at least one of said compartments being in a different plane from the remaining compartments.

In testimony whereof I have signed the foregoing specification.

GEORGE E. HERLIHY.
